NONREFILLABLE BOTTLE

Isaac Buchman, Brooklyn, N. Y.

Application September 22, 1934, Serial No. 745,124

3 Claims. (Cl. 215—14)

The invention relates to a bottle construction and more especially to non-refillable bottles.

The primary object of the invention is the provision of a bottle of this character, wherein the neck has fitted therein a plug or stopper, the latter serving to anchor a mouth closure for the sealing of the mouth of the bottle after the filling thereof, while the original contents of the bottle can be readily and conveniently dispensed at will, it being practically impossible to refill the bottle without destruction to the neck, so that the genuineness of the contents of the bottle in the original filling thereof will be assured.

Another object of the invention is the provision of a bottle of this character, wherein the closure for the mouth of said bottle is of novel construction and affords a permanent seal for the mouth of the bottle to avoid any possibility of a refilling of the bottle through its mouth after the dispensing of the original contents.

A further object of the invention is the provision of a bottle of this character, which is comparatively simple in construction, thoroughly reliable and effective in its purpose, strong, durable, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention, and pointed out in the claims hereunto appended.

In the accompanying drawing:

Figure 1 is a vertical sectional view through a bottle constructed in accordance with the invention, showing the cap removed for the dispensing of the contents of said bottle.

Figure 2 is a view similar to Figure 1 showing the cap applied for the closing of the bottle.

Figure 3 is a sectional view on the line 3—3 of Figure 1 looking in the direction of the arrows.

Figure 4 is a sectional view on the line 4—4 of Figure 2 looking in the direction of the arrows.

Figure 5 is a sectional view on the line 5—5 of Figure 2 looking in the direction of the arrows.

Similar reference characters indicate corresponding parts throughout the several views in the drawing.

Referring to the drawing in detail, the bottle comprises a body 10 which, in its conventional style, is of glass and formed with the neck 11 having the externally reduced mouth 12, and this neck is provided with upwardly divergent dispensing passages 13 for the delivery of the

contents from the body 10 after the filling of such bottle. The mouth 12 accommodates a cap 14 which is either frictionally held upon the mouth or threaded with the neck of the bottle. The cap 14 normally closes the passages 13 to prevent the dispensing of the contents of the body 10 of the bottle until the cap 14 has been removed from the mouth.

The neck 11 has provided therein, a filling bore or opening effecting next to the mouth 12 a circular socket or recess 15, while next to the body 10 is an inwardly tapered bore or passage 16 considerably reduced in diameter with respect to the socket or recess 15. The wall of the socket or recess 15 has diametrically opposite notches 17 for accommodating anchoring pins 18, these being preferably made from metal, while the neck 11 and mouth 12 are of glass.

Accommodated within the socket or recess 15 is an inverted substantially cup-shaped sealing member 19, its side wall slidably accommodating the pins 18. These pins 18 are automatically driven into engagement in the notches 17 by the cone end 20 of a stopper or plug 21 which is fitted within the bore or passage 16. Thus it will be seen that the member 19 will permanently seal the filling opening in the neck of the bottle, while the stopper or plug 21 closes the inner tapered portion 16 of said opening and functions to anchor the member 19 in the socket 15, said member being made from glass while the stopper or plug is made from vulcanized rubber, wood, cork or such like elastic material.

Should any attempt be made to refill the bottle by the breaking of the member 19, which is of glass, for the removal of the stopper or plug 21, the pins 18 having the toothed outer ends 22 will fracture the mouth 12 to render the bottle unfit for further use. It is practically impossible to clear the filling opening of the bottle without damaging such bottle and rendering it unfit for further service.

Normally the bottle has its neck 11 and mouth 12 open and after the filling of the body 10 of said bottle the plug or stopper 21 is placed within the filling opening in the neck so as to fit the portion 16, with the outer cone end 20 projected into the socket or recess 15. Thereafter the member 19 is forced into the socket or recess 15 to become seated therein. The short pins 18, slidably carried by the member 19 have inner conical ends which travel over and compress and slightly groove the cone end 20 of the stopper or plug when said member 19 is being seated.

When the pins are brought opposite the notches 17, they will be forced by the expansion of the plug end 20, therewith. The member 19 is thus permanently anchored in, and seals the filling opening in the bottle neck without danger of the metal pins inflicting injury to the glass member 19 or the neck of the bottle. It is impossible to clear the filling opening of the bottle without damaging the latter, because should pressure be brought to bear upon the member 19, the elastic cone end 20 of the stopper or plug 21 will act as a spreader for the pins 18 and their serrated or toothed outer ends 22 will fracture or break the neck of the bottle to render it unfit for further use.

It, of course, will be seen that the passages 13 will function for the dispensing of the contents of the bottle and the venting of air for the free flow of such contents from the bottle.

20 What is claimed is:

1. A bottle of the kind described comprising a body having a neck forming a filling mouth, a plug carried in the neck and having a cone-shaped expandable spreader tip, a sealing member seated within the mouth and having anchoring pins engaged by the spreader tip for the fastening of the sealing member within the mouth, said neck having dispensing passages opening laterally thereof for the dispensing of the contents of the body, and a closure for the passages and removably fitting said neck.

2. A bottle of the character described comprising a body having a neck formed with a reduced mouth having a filling passage therethrough, a sealing member closing said passage, a plug in said passage, anchoring pins carried by the sealing member and engageable in the neck, and an elastic yieldable spreader tip on the plug designed to yield inwardly when contacted by the anchoring pins when the sealing member is inserted in the passage and thereafter to expand 10 and force the anchoring pins against the neck when the sealing member is fully inserted in the neck. 5

3. A bottle of the character described comprising a body having a neck formed with a reduced 15 mouth having a filling passage therethrough and having a series of notches therein, a sealing member closing said passage, a plug in said passage, anchoring pins carried by the sealing member and engageable in the neck, a compressible 20 and expandable tip on the plug to be first compressed by the anchoring pins when the sealing member is forced into the passage in the neck and thereafter to expand and move the anchoring pins longitudinally to bring the outer ends 25 thereof into the notches, when brought to align with said notches, said neck having dispensing passages, and a closure for said dispensing passages and removably fitted upon the reduced mouth. 30
